UNITED STATES PATENT OFFICE.

OLIVER M. EDWARDS, OF SYRACUSE, NEW YORK.

GEARING.

1,124,116.

Specification of Letters Patent.

Patented Jan. 5, 1915.

Application filed March 16, 1905. Serial No. 250,488.

To all whom it may concern:

Be it known that I, OLIVER M. EDWARDS, a citizen of the United States, residing at Syracuse, county of Onondaga, State of New York, have invented certain new and useful Improvements in Gearing, of which the following is a full, clear, and exact description, reference being had to the drawing accompanying the same.

10 My invention relates generally to the manufacture of gear brackets and has for its objects to provide a bracket adapted to be applied in different desired positions relatively to a window, to construct the gear in parts, to construct the casing in sections, preferably from sheet metal, suitably formed to receive the working parts, and hold them in position when the sections are secured together and also to cheapen the cost of 15 manufacture; and it consists in the combinations of parts or devices hereinafter set forth and particularly pointed out in the claims, which form a part of this specification.

20 Like letters of reference, wherever they occur, indicate corresponding parts in the several figures of the drawing.

Figure 1 shows in front elevation one embodiment of my invention with a part of the 25 casing broken away to show the engagement of the worm with the gear, as in the case where the bracket is made to serve the purposes of the gear bracket shown and described in Letters Patent No. 667,302, Feb. 5, 1901. Fig. 2 shows a blank before being 30 bent into the desired shape, which forms the section or part of the casing which, as here shown, is secured to the window frame or other structure where the bracket is to be 35 used; Fig. 3 shows this same blank after being bent into shape, with portions upstanding to form the sides and portions of the ends of this section of the casing; Fig. 4 shows a longitudinal section on line 4—4 40 of Fig. 3, illustrating the form of the journal bearing for the gear formed in this section; Fig. 5 shows a blank, before bending, which may form the top or other section of the casing; Fig. 6 shows this blank 45 after being bent into shape with its side and end portions upstanding, so as to receive the side and end portions of the other section; Fig. 7 is a longitudinal section on line 7—7 50 of Fig. 6, illustrating the journal bearing 55 for the gear in this section of the casing;

Fig. 8 shows the portion of the gear bearing the teeth, which portion may be formed, if desired, by punching the same from a piece of material of substantially uniform thickness; Fig. 8^a shows in edge view this gear portion seen in Fig. 8; Fig. 9 shows in end view one form of another portion of the gear, illustrating the central opening which receives the shank of the roller or other device to be mounted in the bracket, as well as 60 that portion which receives the gear portion seen in Fig. 8; Fig. 10 shows in side elevation the portion seen in Fig. 9 and illustrates one of the journals to be received by one section of the casing; Fig. 11 shows in end 65 view another portion of the gear containing the other journal and to be received by that portion which receives the gear portion; Fig. 12 shows in longitudinal section the 70 assembled parts, illustrating the preferred 75 form of securing the two sections of the casing together and of thereby holding all of the working parts in position; Fig. 13 shows in side elevation the bracket seen in Fig. 1, with a portion of the top or receiving section 80 of the casing broken away to illustrate the relation of the parts and also of the manner of bending over of certain portions from the positions seen in dotted lines to those seen in full lines to secure the working parts in 85 position; Figs. 14, 14^a and 14^b illustrate another way of securing the two sections of the casing together; Fig. 15 illustrates in end view a tube which may be employed to receive the shank of the roller to be supported 90 by the bracket and also the other portions of the gear.

The casing, as herein shown, is preferably formed from sheet metal or similar material adapted for bending into partial box 95 form, and which may be formed in the desired shape by punches and dies, as is well known. With such material journal bearings may be readily formed of any desired extent of bearing surfaces for the journals 100 which are to work therein, for instance as indicated in Figs. 4 and 7. These bearings are preferably formed while the blank is flat and before the side and end portions are bent up by well known means.

The casing A, as shown, is formed in two sections a and a', preferably of sheet metal, by any desired means of suitable dimensions to receive the intended parts and be manipulated into the desired shapes. The sec- 105 110

tion a' of this casing A, when in the form seen in Fig. 2, is provided with ears by which the bracket may be secured in position, and has formed in it the journal bearing x' to receive one journal of the gear and also the bearings y' to receive the worm B, when the side portions of this section a' are bent, as seen in Figs. 3 and 4. As here shown there are two angular or projecting side portions $e^4 e^4'$ and two angular or projecting end portions $e^2 e^3$, to be bent up at substantially right angles to the remaining or main portions which are preferably substantially flat and of rectangular form.

15 This section, as a' , may be of any desired form or shape adapted to serve the purposes served by the specific shape shown herein, that is, of any shape adapted to receive the working parts and to be secured in different 20 desired positions relatively to a window. The section a of this casing A also has a journal bearing x and bearings $y y$ to receive the gear and worm, respectively, the same as those formed in section a' . The 25 two sections are preferably duplicates of one another in respect to these bearings which receive these parts. This section a also is preferably provided with two angular or projecting side portions $e^4 e^5$, and 30 two angular or projecting end portions, $e^6 e^7$, which may be bent up at substantially right angles to the remaining or main portions and are preferably bent so as to form side and end portions adapted to receive the 35 side and end portions of the section a' , as indicated in Figs. 12 and 13. Preferably this section a has formed on its side and end portions clenching pieces $e^8 e^9 e^{10}$ and e^{11} , which extend beyond such side and end 40 portions and are to be bent over to embrace the under portions of the section a' and clench or secure the two sections together, as indicated in Figs. 12 and 13.

If desired instead of having these casing 45 pieces of sufficient length to bend over and clench the two sections together, as shown in Figs. 12 and 13, they may be otherwise made, for instance, so that the portions, as e^{20} of section a may pass through opening e^{21} in section a' and rivet or clench as indicated in Figs. 14, 14^a and 14^b. The portions of section a' in which the slots e^{21} are formed are separable from adjacent portions by slits e^{22} thereby forming portions 55 e^{23} which are to be bent up into the form seen in Fig. 14 and serve the same functions as are served by the portions e^2 in preceding figures.

The worm B may be formed by any desired 60 means, and provided with any desired shape or form of end portion or portions by which such worm may be conveniently rotated. As shown this worm is provided with elongated squared and slotted end portions b, b' , which may be taken hold of to

rotate the worm, or, if desired, a tool of suitable shaped engaging portions, as a screwdriver or wrench may be used in connection with such ends to rotate such worm, and thereby rotate the gear. Suitable shoulders, as b^2 and b^3 , are formed adjacent to such squared or slotted ends which engage with the exterior surfaces of the side portions e^4 and e^5 of casing section a and prevent undue end motion of such worm in its bearings in the casing by the end thrust given to the worm by the gear C in forcing such gear to rotate. The end portions of this worm are shown as duplicates of one another, so as to be received in the casing 80 with either end pointing in a given direction. It is of course obvious to any mechanic that either a screwdriver or suitable wrench may be employed on the specific end portions of this worm B here shown and 85 also that either the slot or square end portions can be used with like effect and that when the slot is employed without the squaring of such portions the screwdriver alone would be used. This gear C, as here 90 shown, is composed of three parts or portions, the gear portion c , the receiving portion c' and loose journal portion c^2 . The gear portion c , as here shown, is made with substantially straight teeth and is therefore 95 adapted to be placed either side up on the receiving portion c' , in assembling the parts together. Furthermore this gear portion c may be formed by punches and dies into the form herein shown, if desired, and the 100 cost of making each individual portion be very much reduced over what would be the case by forming such portion by other means adapted to give equally good working results. Of course this portion c may be 105 formed otherwise than as just described, but the above is the preferred way.

The receiving portion c' is shown in Figs. 9 and 10, as being formed integral with one of the journals c^3 and with a central opening the whole length of this portion c' , which opening is adapted to receive the shank of one end of a shade roller or similar formed part and to prevent the same turning therein and causing such shank portion to rotate with the gear C of which this portion c' forms a part. A portion of this part c' is provided with the journal c^3 which is adapted to be received in one of the casing sections journal bearings x and x' , and it has a shoulder to prevent its outward movement from the casing A in an endwise direction, as indicated in Fig. 12. The journal portion c^2 is formed with a journal bearing and shoulder corresponding to that on portion c' and is received by this latter portion and holds the gear C from endwise motion in one direction, also as is indicated in Fig. 12, where this gear C is shown in longitudinal section with the 130

parts assembled in place and the worm B seen in cross section. It will be obvious to a mechanic that the construction of this casting ready to receive the working parts will 5 be the same whether each of such parts (worm and gear) is made from one piece of material or of different pieces, for in each case they are received by the casing as a single piece.

- 10 Instead of making the journal and tubular portions of the receiving portion c' from one piece of material they may, if desired, be otherwise made, as for instance of two pieces, one tubular and the other a substantial 15 duplicate of the loose journal portion c^2 , seen in Fig. 11, which is to be forced onto the tubular portion c^5 , seen in Fig. 15, in a well known manner of forcing one piece of material onto another piece, so that the 20 two may act as a single piece would act. It is preferred that these gear parts shall be formed so as to go either end up in the assembling of the same in the casing, but they may be constructed in any desired manner, so long as the gear as a whole may 25 serve the functions served when constructed as herein shown.

When constructed as herein shown, to assemble the parts and secure the working parts in position, it is only necessary to take 30 a casing section a' , as shown in Fig. 3, place a gear C, either end up, in the journal bearing x' , a worm B in bearings $y' y'$ and then take a casing section a , as seen in Fig. 6, 35 and place it, with its angular or projecting side and end portions e^4, e^5, e^6 and e^7 pointing toward the side and end portions e, e', e^2 and e^3 , so as to receive the same and force the two sections toward each other 40 and cause the journal bearing x , in section a , to receive its journal end bearings $y y$ receive or pass over the journal portions of the worm B with the shoulders b^2 and b^3 of this worm outside of the side portions e^4 45 and e^5 of casing section a , all as seen in Fig. 1. Then by bending over the clenching pieces e^8, e^9, e^{10} and e^{11} , as indicated in Figs. 12 and 13, the two sections of the casing A are firmly secured together and the working 50 parts, worm B and gear C, are secured in working position. This construction of casing, worm and gear permit of the structure, as a whole, being mounted in different positions with suitable access given to the worm to operate and actuate the gear to 55 the desired extent. For instance the casing and combined parts may be used at either the right or the left side of a window with equal facility, or they may be used with the worm substantially at right angles or parallel with the direction of movement of the sash in opening and closing the windows, or in any other direction desired to give ready 60 access to the worm to operate the same by hand or a tool suitable for the purpose.

It will be obvious to a mechanic that the ear portions by which the casing, as A, is secured in position may be of any desired shape and arranged in any desired manner relatively to the other portions of the casing, so long as they are adapted to hold such casing in place in the particular position or positions it is desired to place it.

That which is herein set forth will naturally suggest to those skilled in the art 70 changes or modifications in what is shown and described, but I desire to include within my invention all constructions which come within the spirit thereof and have the parts combined together with the mode of 75 operation herein set forth and particularly pointed out in the claims forming a part of this specification, and, therefore, I do not wish to limit myself to that which is herein specifically shown and described.

What I desire to claim as new is:—

1. In a bracket, the combination of a casing composed of two interfitting sections, each section having a journal bearing adapted to be brought into alinement with 90 the journal bearing on the other section to support the opposite ends of a rotatable member when the sections are fitted together, substantially as and for the purpose described.

2. In a bracket, the combination of a casing composed of two interfitting sections, each having angular projecting portions, the portions of one fitting within the portions of the other and such portions being formed 95 with openings adapted to be brought into alinement when the sections are fitted together, the alined openings forming a bearing for the rotatable part, substantially as and for the purpose specified.

3. In a bracket, the combination of a casing comprising two interfitting sections, each having a bottom and sides, and each section being formed with a journal bearing in its bottom, and with openings in its opposing 110 sides, the journal bearings and openings of each section being located to be brought into alinement with the journal bearing and openings respectively of the other section when the sections are fitted together, substantially 115 as and for the purpose set forth.

4. In a bracket, the combination of a casing including two interfitting sections, each comprising a substantially flat main portion and projecting sides, and the sides of one 120 interfitting with the sides of the other and the edges of the sides of one bearing against the main portion of the other section when the sections are fitted together, the opposing sides of one being formed with slots open at 125 one end and the sides of the other having means for closing the open ends of the slots, the slots forming a bearing for a rotatable member, substantially as and for the purpose described.

5. In a bracket, a casing, formed of two interfitting sections, each comprising a substantially flat main portion and opposing projecting sides formed with slots opening through their free edges, the sides of one section being located to fit within the sides of the other and rest against the main portion thereof when the sections are fitted together, and the slots of the sides of the two sections being reversely arranged so that the walls of the slots of the two sections form a closed bearing for a rotatable member, substantially as and for the purpose specified. 6. In a bracket, the combination substantially as set forth, of a casing comprising two interfitting sections, each being formed with a bottom and sides, and the bottom of each section being formed with a journal bearing, and the sides being formed with slots opening through the free edges thereof, and the sides of one section being located to fit within the sides of the other section when the sections are fitted together, and the journal bearings in the bottoms of the two sections being located to come into alinement, and the slots and the sides of the two sections being located to come into alinement, when the sections are fitted together, substantially as and for the purpose set forth. 7. In combination, a casing having bearings in its opposite side walls, a worm having bearing portions at opposite ends thereof, either of which coöperates with the bearing in either side wall of the casing, said casing also being provided with bearings for a gear, and a gear mounted in the casing in mesh with the worm and having duplicate bearing portions coöperating with the gear bearings, substantially as and for the purpose described. 8. In combination, a casing comprising two sections having duplicate bearings in the side walls thereof, a worm having duplicate end portions, either of which coöperates with the bearings in either side wall of the casing, said casing being also provided with gear bearings, a gear located in the casing in mesh with the worm and having duplicate end bearing portions, either of which coöperates with either of the gear bearings of the casing, and means for securing the two sections of the casing together with the worm and gear clamped in position between the same, substantially as and for the purpose specified. 9. In a bracket the combination, substantially as set forth, of a casing, a worm mounted in the casing, and a gear made in parts, the part meshing with the worm being made of material of substantially uniform thickness and adapted to be mounted in re-
- verse positions relatively to the other parts in the casing. 10. In a bracket the combination, substantially as set forth, of a casing composed of two sections of bent sheet metal, portions of which are adapted to receive and hold a worm and afford means of securing the two sections together, each of which sections is provided with a journal bearing adapted to receive either journal of a gear, a worm provided with duplicate end portions, and a gear provided with similar journal bearings adapting it to be mounted in the casing either side up and mesh with the worm. 11. In a bracket the combination, substantially as set forth, of a casing in two parts adapted to be secured together, a worm adapted to be received in the casing either end to, and a gear adapted to mesh with the worm and to be received in the casing with its toothed portion either side up, which worm and gear portions are held in working positions by securing the two parts of the casing together. 12. In a bracket the combination, substantially as set forth, of a casing in two parts means adapted to secure such parts together, a worm, and a gear adapted to mesh with the worm and composed in part of journal portions, one of which is separate from the other, and a separate gear portion adapted to be mounted between the journal portions, which are to be received by the casing and thereby held in workable relation to the worm. 13. In a bracket the combination, substantially as set forth, of a casing in two parts, means adapted to secure the parts together, a worm, and a gear provided with teeth adapted to mesh with the worm, when assembled either side up relatively thereto, and composed of separate parts adapted to be received in the casing and thereby held in workable relation to the worm. 14. In a bracket the combination, substantially as set forth, of a casing in two parts, means adapted to secure such parts together, a worm, and a gear composed of separate parts consisting of journal portions, one of which is provided with means to engage with a part and rotate the same and receive other portions of such gear and a portion provided with teeth adapted to mesh with the worm and also provided with means adapted to rotate a journal portion upon the rotation of the worm.
